UNITED STATES PATENT OFFICE.

FREDERIC CONDÉ, OF OSWEGO, NEW YORK.

DESIGN FOR A KNITTED FABRIC.

No. 38,047.

Specification for Design.

Patented May 29, 1906.

Application filed April 3, 1906. Serial No. 309,711. Term of patent 7 years.

To all whom it may concern:

Be it known that I, FREDERIC CONDÉ, a citizen of the United States, residing at Oswego, in the county of Oswego, State of New York, have invented a new and original Design for Knitted Fabrics, of which the following is a specification, reference being had to the accompanying drawing.

The design is illustrated in the accompanying drawing, in which the figure is an elevation of a portion of a knitted fabric, showing my new design.

I claim—

The ornamental design for a knitted fabric, substantially as shown.

FREDERIC CONDÉ.
